UNITED STATES PATENT OFFICE.

BERNARD A. STERLING, OF CHICAGO, ILLINOIS.

DESIGN FOR A HOLDER FOR MANICURING PREPARATIONS.

53,973.

Specification for Design.

Patented Oct. 14, 1919.

Application filed September 3, 1918. Serial No. 252,496. Term of patent 14 years.

To all whom it may concern:

Be it known that I, BERNARD A. STERLING, a citizen of the United States, residing at Chicago, in the county of Cook and State of Illinois, have invented a new, original, and ornamental Design for a Holder for Manicuring Preparations, of which the following is a specification, reference being had to the accompanying drawing, forming a part thereof.

The figure is a perspective view of a holder for manicuring preparations, showing my new design.

I claim:

The ornamental design for a holder for manicuring preparations as shown.

BERNARD A. STERLING.
